UNITED STATES PATENT OFFICE.

CLARENCE P. BEROLZHEIMER, OF CHICAGO HEIGHTS, ILLINOIS.

TIP FOR BRAID OR THE LIKE.

Application filed December 7, 1921. Serial No. 520,536.

To all whom it may concern:

Be it known that I, CLARENCE P. BEROLZHEIMER, a citizen of the United States, residing at Chicago Heights, in the county of 5 Cook and State of Illinois, have invented a new and useful Tip for Braid or the like, of which the following is a specification.

This invention relates to improvements in tips for braid or the like, particularly tips 10 for shoe laces or other similar objects which will possess characteristics of unbreakable-ness combined with permanency in that the same will constitute an inherent part of the material of the braid.

15 A special object of this invention is the provision of a tip for braid or the like which, even when broken, will present a portion available as a point for threading same through an eyelet or the like, even 20 after this breaking off has repeatedly occurred.

Another object of this invention is the provision of an improved tip for braided material which shall act to efficiently prevent the fraying of the ends of such braided material and the consequent unraveling of same which constitutes one of the most disagreeable features attending upon the use of this class of goods.

30 A still further object of this invention is the provision of a tip for braid or the like which can be readily and simply applied in either a powdered or plastic condition and which, after it has been applied, will so 35 impregnate the material of the braid by hardening to an insoluble mass as to prevent a hard practically solid and irremovable tip or point for the same.

Another important object of this invention 40 is the provision of a tip such as described and composed of preferably a phenol condensation product, which, when applied to the braid by heat and pressure, will combine with the same and form an integral 45 part thereof.

Other and further important objects of this invention will be apparent from the disclosures in the accompanying drawing and following specification.

50 The invention, in a preferred form, is illustrated in the drawings and hereinafter more fully described.

In the drawings:

Figure 1 is a perspective view of a tip as 55 applied to a piece of braid in accordance with this invention.

Figure 2 is a sectional view taken on the line 2-2 of Figure 1.

Figure 3 is a side elevation showing a modification of the invention.

Figure 4 is a sectional view taken on the line 4-4 of Figure 3.

Figure 5 is a view showing a unitary improved tip as applied to and joining a plurality of strands of material.

As shown in the drawings:

The improved form of tip is preferably composed of a material which, upon the application of heat and pressure, will harden into an infusible, insoluble mass. This material is preferably composed of a phenol condensation product or of a product of a phenol and hexamethylenetetramine, formaldehyde, or any similar compounds which react in a like manner, as casein and formaldehyde, naphthalene and chlorine, etc.

This material is preferably applied to the braid, lace, rope, twine, or the like in powdered form by means of a specially constructed set of dies adapted to apply simultaneously the requisite heat and pressure.

In the preferred form of the invention shown in Figures 1 and 3 the tip, as indicated on the drawings, is composed of a phenol condensation product in its final infusible state and the construction of the dies for forming said feature is such that the same will be square in cross-section as best shown in Figure 3.

In Figures 2 and 4 the cross-section of the final tip is shown as circular and it is evident that any shape of tip may be constructed without departing from the main idea of this invention. For example, the tips may be hexagonal or of any other desired shape.

It is evident that this or similar material may be applied to any particular form or size of braided material including laces, braids, cord of any size, rope, or any other allied products, as leather, etc. The only change in the procedure being the substitution of different sizes of dies in the forming process to correspond with the size or number of strands of material used.

The square cross section of the tip is particularly preferred as it has been found through experiment that this shape is more easily handled and will afford a firmer grip to the user whether the tip be applied to a shoe lace or a heavy rope. In heavy work especially, the square form is particularly

adapted to finishing or working the product.

It will be evident that this form of tip constitutes a valuable improvement upon the metallic tips heretofore in use which con-

tinually come off, especially as applied to shoe laces or the like, to the great annoyance of the user thereof. Moreover, a tip formed of a hard infusible material, such as a phenol condensation product, or any allied 10 substance in the nature of a synthetic resin, constitutes a material advance over tips formed by impregnating braid or the like with glue or binder or by the application of celluloid thereto, which last named material, 15 besides being inflammable, soon works off in use and is additionally undesirable in view of the difficulty of application. This tip, if desired, may be the condensation product of a drying oil, as soy bean oil, tung 20 oil, or the like, and an amine as soy glucin and formin.

By the improved process of this invention the tip material is applied in powdered or plastic form, this being its intermediate state 25 of manufacture in which form it is both soluble and fusible but upon the application of a certain amount of heat and pressure,

will assume its final insoluble infusible state, after having thoroughly impregnated the material of the braid itself.

I am aware that many changes may be made and numerous details in the method of application of this material to the braid varied without departing from the principle of this invention and I therefore do not propose to limit the scope of this invention otherwise than as shown by the prior art.

I claim as my invention:

1. A shoe lace provided with integral tips of square cross section, said tips composed of a phenol condensation product.

2. A tip for shoe laces integral with the material of the lace and of square cross section, said tip comprising a phenol condensation product fused into the material by heat and pressure.

In testimony whereof I have hereunto subscribed my name in the presence of two subscribing witnesses.

CLARENCE P. BEROLZHEIMER.
